US0D1031445S

(12) **United States Design Patent** (10) **Patent No.:** **US D1,031,445 S**
(45) **Date of Patent:** **** Jun. 18, 2024**

(54) **MULTIFUNCTIONAL BOTTLE**

(71) Applicant: **PWBL, LLC**, Swampscott, MA (US)

(72) Inventor: **Teofilo Nunez**, Swampscott, MA (US)

(73) Assignee: **PWBL, LLC**, Swampscott, MA (US)

(**) Term: **15 Years**

(21) Appl. No.: **29/841,072**

(22) Filed: **Jun. 2, 2022**

(51) **LOC (14) Cl.** **07-01**

(52) **U.S. Cl.**

USPC **D7/513; D9/741**

(57) **CLAIM**

The ornamental design for a multifunctional bottle, as shown and described.

DESCRIPTION

FIG. 1 is a top front right side perspective view of a multifunctional bottle;

FIG. 2 is a bottom rear left side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a top front right side perspective in an open configuration view thereof.

The broken lines shown in FIG. 9 on the drawings depict portions of a multifunctional bottle that form no part of the claimed design.

1 Claim, 6 Drawing Sheets
